US00D359475S

United States Patent [19]

Coffey

[11] Patent Number: Des. 359,475

[45] Date of Patent: ** Jun. 20, 1995

[54] PATCH PANEL

[75] Inventor: Joseph C. Coffey, Old Fort, N.C.

[73] Assignee: Superior Modular Products Incorporated, Swannanoa, N.C.

[**] Term: 14 Years

[21] Appl. No.: 19,108

[22] Filed: Feb. 23, 1994

[52] U.S. Cl. D13/154

[58] Field of Search ..... D13/154, 147, 177, 184; D8/364; 361/810, 822, 828, 829, 758; 439/44, 45, 47, 49, 50, 74, 536, 540; 174/138 D

[57] CLAIM

The ornamental design for the patch panel, as shown and described.

DESCRIPTION

FIG. 1 is a three dimensional perspective view generally of the rear side of a patch panel in accordance with a first embodiment of my invention;

FIG. 2 is a plan view of the rear side of the patch panel in accordance with the first embodiment of my invention;

FIG. 3 is a plan view of the front side of the patch panel in accordance with the first embodiment of my invention;

FIG. 4 is a side elevational view of the patch panel in accordance with the first embodiment of my invention;

FIG. 5 is a three dimensional perspective view generally of the rear side of a patch panel in accordance with a second embodiment of my invention;

FIG. 6 is a plan view of the rear side of the patch panel in accordance with the second embodiment of my invention;

FIG. 7 is a plan view of the front side of the patch panel in accordance with the second embodiment of my invention;

FIG. 8 is a side elevational view of the patch panel in accordance with the second embodiment of my invention;

FIG. 9 is a three dimensional perspective view generally of the rear side of a patch panel in accordance with a third embodiment of my invention;

FIG. 10 is a plan view of the rear side of the patch panel in accordance with the third embodiment of my invention;

FIG. 11 is a plan view of the front side of the patch panel in accordance with the third embodiment of my invention; and,

FIG. 12 is a side elevational view of the patch panel in accordance with the third embodiment of my invention.
